US00D764435S

(12) **United States Design Patent**
Brunner et al.

(10) **Patent No.:** **US D764,435 S**
(45) **Date of Patent:** **** Aug. 23, 2016**

(54) **GAMING HEADSET**(71) Applicant: **Apple Inc.**, Cupertino, CA (US)(72) Inventors: **Robert D. Brunner**, San Francisco, CA (US); **Christopher Kuh**, San Francisco, CA (US)(73) Assignee: **Apple Inc.**, Cupertino, CA (US)(***) Term: **14 Years**(21) Appl. No.: **29/504,827**(22) Filed: **Oct. 9, 2014****Related U.S. Application Data**

(60) Continuation of application No. 29/464,539, filed on Aug. 18, 2013, now Pat. No. Des. 716,760, which is a division of application No. 29/426,082, filed on Jun. 29, 2012, now Pat. No. Des. 691,112, which is a continuation-in-part of application No. 29/410,585, filed on Jan. 9, 2012, now Pat. No. Des. 698,749.

Primary Examiner — Paula Greene(74) *Attorney, Agent, or Firm* — Sterne, Kessler, Goldstein & Fox P.L.L.C.(57) **CLAIM**

The ornamental design for a gaming headset, as shown and described.

DESCRIPTION

FIG. 1 is a perspective view of a gaming headset showing the claimed design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the gaming headset that form no part of the claimed design.
